ABSTRACT

A railway car with elastic side walls for carrying crops and discards coming from cutting of flat bloom ends by a slabbing mills, which crops and discards are collected by a movable box container which collects and carries said materials and then discharges them onto a special railway car.

1
RAILWAY CAR WITH ELASTIC SIDE WALLS

BACKGROUND OF INVENTION

The present invention consists in a railway car with elastic side walls for carrying crops and discards coming from a slabbing mill.

As said crops, the weight of which may reach up to one ton, pass from said containers onto railway cars by falling freely from a height of 3-5 meters, the need arose of substituting for the conventional railway cars with stiff side walls special cars the side walls of which, carefully designed as for their shape and size, could bend so as to transform the kinetic energy of the falling body into an elastic deformation energy of the striken side wall element and adjacent ones, removing thus from said action the strike effect and consequently avoiding any permanent deformation.

20
SUMMARY OF INVENTION

The object of the present invention is to provide a railway car with elastic side walls for carrying crops and discards coming from a slabbing mill comprising a stiff frame on which are fastened shaped sheet strips, according to their longitudinal direction, substantially C-shaped, which are arranged adjacent to each other transversally to the car longitudinal direction and are connected to each other by at least a pair of longitudinal sheet strips extending preferably between the car ends.

Said sheet strips, shaped according to their longitudinal direction, are C-shaped and comprise exactly a horizontal rectilinear central section with at the ends thereof two rectilinear upward inclined sections, two curved sections and finally two further rectilinear sections substantially vertical though slightly inclined towards the car inside.

The rectilinear central section of said shaped strips is connected to the car frame, correspondingly to the ends of said rectilinear central section preferably by bolts; the ends of said shaped strips being connected to each other, each by a sheet strip arranged longitudinally to the car axis, which is securely connected to the car head walls; the connection between the longitudinal strips and the shaped strips being obtained preferably by bolts.

Between each shaped strip and the adjacent one there is left a free gap which is large as the strip width and preferably as wide as a fraction of said width.

The car frame comprises a substantially stiff framework covered on its top by a continuous sheet; on the two long sides of the car being arranged two low side walls suitable to contain, together with the car head walls, a layer of filling materials, preferably represented by slags.

The car head walls are made of channel-shaped sections arranged horizontally and overlapped to each other with their concavity directed towards the car outside; suitable stiffening uprights being arranged on the outer faces of said head walls.

BRIEF DESCRIPTION OF THE DRAWINGS

The accompanying drawings show, by way of example only, an embodiment according to the above-described objects.

5
FIG. 1 is a partial plan view of a railway car according to the invention;

FIG. 2 is a partial side view of said car;

FIG. 3 is a view taken from the left of FIG. 2, that is a view of the forward end of said car;

FIG. 4 is a semi-sectional view taken along plane IV-IV of FIG. 1;

FIG. 5 is a semi-sectional view, similar to FIG. 4, taken along plane V-V of FIG. 1, close to the car head wall, so that the latter may be seen from inside;

FIG. 6 is a simplified sectional view taken along plane VI-VI of FIG. 1 in a reduced scale;

FIG. 7 is a partial sectional view taken along plane VII-VII of FIG. 1;

FIG. 8 is a plan view, in a reduced scale, of the car end with the elastic side walls removed;

FIG. 9 is a partial sectional view in an enlarged scale taken along plane IX-IX of FIG. 1, and

20
FIG. 10 is a sectional view taken along plane X-X of FIG. 7.

DESCRIPTION OF THE PREFERRED EMBODIMENT

In the above listed figures, which relate to a single particular solution of a railway car improved according to the invention, numeral 1 denotes a set of sheet strips longitudinally C-shaped and comprising a flat central section 101, an upward inclined side section 102, a connection joint 103 and finally a rectilinear section slightly inclined towards the car inside and acting as a side wall portion. Said elements are to be arranged adjacent to each other, transversally to the car longitudinal axis, and between each pair of adjacent elements a gap 104 is left free; each of said shaped strips is fastened to the car bearing structure, in this case to the upper wings of beam 106 by means of four bolts 19 shown only diagrammatically in the figure. The shaped strips 1 are connected to each other by means of a pair of sheet strips 2 which join longitudinally the upper end of section 104 of each shaped strip 1; said strip 2 is connected to the shaped strips 1 by means preferably of bolts 20 shown only diagrammatically in the figure; the use of bolts allows a relatively simple and quick replacement of the shaped strips 1 which ought to be replaced being broken, warped and the like.

The two ends of strips 2 are securely fastened, still by means of bolts 33, to the car head walls formed by channel shaped sections 3 overlapped to each other and with their wings directed towards the car outside, through suitable coupling plates 32; the two head walls are connected to two short and stiff side members formed in the same way as the head walls, obtained by means of lugs 4 of channel-shaped sections 3. The frame 18 of the car is covered at its top by a continuous sheet 17 intended for collecting chips of materials of any kind, and particularly, together with two sheets 8 acting as side walls, it may contain a filling 107 where sheets are partly immersed into, said filling being further suitable to absorb the shocks caused by the workpieces falling onto the bottom concerned.

Numerals 5, 6 and 7 denote metal sections acting as stiffening uprights for the two head walls of the car; in order to reinforce the connection between said uprights and the channel-shaped sections forming the

head walls, reinforcing plates 11, stiffened by elements 12, are arranged in the groove of sections 3, and on said plates said uprights are welded.

Numerals 13, 14 and 15 denote the stud of a ladder, the coupling and the steps thereof respectively.

The arrangement works as follows: the crops and discards coming from cutting of flat bloom ends fall onto the described car hitting the bottom and side walls thereof, said walls under the shock action are capable of deforming elastically not only locally, as each of shaped strips 1 is connected to the shaped strips adjacent thereto through strips 2 which take part in said deformation.

The slag filling the car bottom is suitable to absorb the direct shocks which otherwise would be suffered by the central portion of the car bottom which is not in position to deform elastically.

Obviously, the form of the shaping of strips 1 may be modified, as well as the number of strips 2 joining said strips 1.

What is claimed is:

1. A railway car having a rigid frame, two longitudinally extending frame elements one at each side of the car, a plurality of c-shaped panels disposed transversely of the car and secured at their ends to said elements, each panel being unsupported by an adjacent panel whereby under impact from the interior of said car said panels will flex, said car also comprising a base upon which is disposed shock absorbing materials within which the lowermost portions of the panels are disposed.

2. A railway car having a rigid frame, two longitudinally extending frame elements one at each side of the car, a plurality of c-shaped panels disposed transversely of the car and secured at their ends to said elements, each panel being unsupported by an adjacent panel whereby under impact from the interior of said

car said panels will flex, said car having end walls constituted by channel section bars mounted one atop another and with their flanges disposed to the exterior of the car.

5. A railway car comprising a wheeled frame opposed end walls, a pair of longitudinally extending flat frame elements connected to the upper corners of the end walls, a plurality of c-shaped panels extending transversely of the car, having their ends secured to 10 said frame elements, being secured at their midpoints to a central longitudinal frame element and being unsupported at their edges and each panel being spaced from an adjacent panel, a base below the panels and supporting a shock absorbing material thereon within 15 which material the lowermost portions of said panels are disposed.

4. A railway car as claimed in claim 3 wherein each of said panels comprises a generally flat mid portion, upwardly inclined generally flat portions to each side of 20 said mid portion and generally flat side portions which incline inwardly towards each other, said side and inwardly inclined portions being joined by a curved portion.

5. A railway car having a rigid frame, two longitudinally extending frame elements one at each side of the car, a plurality of c-shaped panels disposed transversely of the car and secured at their ends to said elements, each panel being unsupported by an adjacent panel whereby under impact from the interior of said car said panels will flex, said panels comprising a generally flat mid portion, upwardly inclined generally flat portions to each side of said mid portion and generally flat side portions which incline inwardly towards each other, said upwardly inclined side portions being joined by a curved portion, and wherein said mid portion is secured to a central longitudinally extending frame element.
